UNITED STATES PATENT OFFICE.

WILLIAM H. CROPPER, OF WELLSBURG, WEST VIRGINIA.

DESIGN FOR A BOTTLE.

SPECIFICATION forming part of Design No. 26,924, dated April 20, 1897.

Application filed March 6, 1897. Serial No. 626,328. Term of patent 7 years.

To all whom it may concern.

Be it known that I, WILLIAM H. CROPPER, a citizen of the United States, residing at Wellsburg, in the county of Brooke and State of West Virginia, have invented and produced a new and original Design for a Bottle, of which the following is a specification, reference being had to the accompanying drawings, forming a part thereof, in which—

10 Figure 1 is a side elevation of a bottle embodying the features of my design. Fig. 2 is a bottom plan view of the bottle, and Fig. 3 is a transverse section through the body of the bottle.

15 The design is intended as an attractive improvement in the formation of glass bottles, the design being of such character that through a combination of curved surfaces a beautiful effect is obtained, and, further, by 20 reason of said curved surfaces there is less liability of breakage than in a bottle fashioned after the ordinary designs, namely, having sharp edges or angles.

The upper shoulder A' of the body A of the bottle is curved or given a convexed formation, as is likewise the bottom shoulder B. The bottom C of the bottle, which is flat, has an elliptical marginal contour. 25

A further feature of the design consists in the convexed sides D, the duplication of elliptical lines e at the bottom, and the formation of longitudinal ribs E at the transverse meeting of the sides, the outer face of the ribs being transversely convexed, and the said ribs conforming at their ends to the curvature of 30 the top and bottom shoulders A and B. 35

I claim—

The design for a bottle herein shown and described.

WILLIAM H. CROPPER.
